UNITED STATES PATENT OFFICE

CELESTIN BERNE, OF BRIDGEPORT, CONNECTICUT, ASSIGNOR OF ONE-HALF TO MAURICE DANIELLS, OF MILFORD, CONNECTICUT

DETACHABLE SPRING HINGE

Application filed January 27, 1932. Serial No. 589,160.

My invention relates to hinges and more particularly to spring hinges such as are commonly used on screen and storm doors and has for its object to provide a novel form of separable hinge whereby a door may be readily detached from its casing without the necessity of removing a number of screws from the door or casing, as is usually customary, and wherein it is only necessary to 10 operate thumb screw for the releasement of each hinge from the casing and whereby the door and its attached hinges may be readily taken down.

The hinge for the most part is constructed 15 along the usual conventional lines comprising two sections or leaf members hingedly connected together and having a pivotal pin and coil spring that normally holds the leaves in aligned relation and when attached to a door 20 tends to hold the same closed.

My invention more specifically resides in the employment of a specially formed plate adapted to be permanently attached to a door casing, or the door if desired, and to adapt 25 one of the leaves of the hinge for positioning and removable attachment to the plate whereby the hinge and its attached door may be conveniently and quickly attached to the plate and door casing.

With these and other objects in view, the invention resides and consists in the construction and novel combination and arrangement of parts hereinafter more fully described, illustrated in the accompanying drawing, and 30 pointed out in the claims hereto appended, it being understood that various changes in the form, proportion, size, and minor details of construction within the scope of the claims 35 may be resorted to without departure from the spirit, or sacrificing any of the advantages of the invention. Similar characters of reference denote like or corresponding parts throughout the several figures of the accompanying drawing forming a part of this specification and upon which

Fig. 1 shows a front elevation of my improved detachable spring hinge, shown applied to a portion of a door casing and screen 50 door;

Fig. 2 is a side view, as seen from the left, Fig. 1, though in a horizontal position;

Fig. 3 is a cross sectional view, through the hinge including the attaching plate, taken on line 3—3 of Fig. 1;

Fig. 4 is a plan view of the plate member of the hinge detached; and

Fig. 5 is a detail showing a modified form of means for clamping the hinge leaf and plate together.

Referring more particularly to the drawing in which like characters of reference denote corresponding parts throughout the several figures. 10 represents a portion of a door casing and 11 a small section of a screen door and to both of which parts my improved detachable spring hinge is shown attached. 12 represents the leaf of the spring which is shown attached to the door 11 by means of screws 13. 14 represents the companion leaf member which is in part of special construction, but like the member 12 is provided at its opposite end portions with outwardly disposed ears or flanges 15.

Corresponding flanges 16—16 of the member 12 are positioned against the inner sides of the flanges 15 and all of the said flanges are provided with aligned holes to receive the pivotal pin 17 upon which a coil spring 18 is positioned, one end portion 19 being disposed against one leaf 12 of the spring and the other end 20 being disposed upon the other leaf 14, the inner edge portions 21 of the leaves being adapted to engage and limit the action of the spring.

The base portion of the leaf 14 is deflected or bowed as at 22, and is provided with an elongated opening 23. The underface 24 of this base portion of the leaf 14 normally lies slightly above the underface of the companion leaf member 12, so as to provide space for the plate 25 to which the hinge is attached. This plate is elongated as shown and like the leaf 14, is preferably bowed crosswise of its length, but not quite as much as that of the leaf member so that in the loose assembling of the two parts there remains a space between the two to allow for the clamping action which is effected by the operation of the thumb screw 26 positioned upon the

top side of the base 14 and whose threaded screw end engages a flange nut 27 that is positioned in a shouldered hole of the plate and against the underside of the plate.

6. The thumb screw, as will be seen, is flanged to form an elongated engaging surface 28 that is adapted to freely pass through the elongated opening of the member 14 and be turned against the inclined surfaces of the 10 edge portion of the opening in the leaf in a way to draw the yieldable deflected portions of the leaf and plate members together, with a clamping action, and which serves to secure the leaf to the plate. Any suitable form of 15 clamping means may be employed such for instance as a winged thumb screw and nut, as shown in Figs. 2 and 3, or a winged nut and headed screw, as shown in Fig. 5, or in fact a simple form of levered cam, not shown, 20 could be employed.

The plate is provided with screw holes 29 for its permanent attachment to a door frame and is provided with outwardly projecting bosses 30 upon its side and end portions, see 25 Figs. 1, 2 and 4, intermediate of which the leaf member of the hinge is positioned and held against vertical or lateral movement, preparatory to as well as after the clamping operation.

30. The hinge is preferably constructed of sheet metal and therefore both the deflected or bowed base member of the leaf 14 and the retaining-plate 25 are more or less flexible and adapted to be drawn together by the 35 screw with a yielding resistance in a way to insure a firm clamp action of the two parts. This result may also be obtained if but one of the members be deflected, as for instance the leaf member, and whereby a yieldable 40 straight-plate could be as effectively clamped as long as there was ample space between the bowed leaf member and said straight-plate.

Having thus described my invention, what 45 I claim and desire to secure by Letters Patent is:

1. A detachable spring hinge, comprising in part, two leaf members hingedly connected together, the base portion of one of the said leaf members including a deflected 50 yieldable portion provided with an opening therethrough, a yieldable retaining-plate for permanent attachment to a door frame, upon which the said deflected leaf is positioned, and clamping means carried by said plate 55 and adapted to enter the opening and be operated to clamp the deflected leaf and plate together.

2. A detachable spring hinge, comprising two leaf members hingedly connected together, a coiled spring attached thereto to retain the two said leaf members in normal 60 positions, the base portion of one of said leaf members including an outwardly deflected yieldable portion provided with an 65 opening therethrough, a yieldable retaining-

plate for permanent attachment to a door frame upon which the yieldable leaf member is mounted, and clamping means carried by said plate and adapted to enter the opening and clamp the deflected leaf and plate 70 together.

3. A detachable spring hinge, comprising two spring actuated leaf members hingedly connected together, the base portion of one of said leaf members including a deflected yieldable portion provided with an opening therethrough, a deflected yieldable retaining-plate for permanent attachment to a door frame, upon which the said deflected leaf is positioned and clamping means carried by said plate and adapted to enter the opening and clamp the deflected leaf and plate together. 75 80

4. A detachable spring hinge, comprising two spring actuated leaf members hingedly connected together, the base portion of one of said leaf members including an outwardly deflected yieldable portion provided with an opening therethrough, a yieldable retaining-plate for permanent attachment to a door frame upon which the yieldable leaf member is mounted, said plate being provided with lugs to engage the edge portions of the leaf to hold it in place, and clamping means carried by said plate and adapted to enter the opening and be operated to clamp the deflected leaf and plate together. 85 90

5. A detachable spring hinge, comprising two spring actuated leaf members hingedly connected together, the base portion of one of said leaf members being bowed and yieldable and provided with an elongated opening therethrough, a yieldable bowed retaining-plate for attachment to a door frame and designed to support said bowed leaf member in yieldable spaced relation, clamping means carried by said plate and adapted to enter the opening and be operated to clamp the deflected leaf and plate together. 95 100

Signed at Bridgeport, in the county of 105 Fairfield and State of Connecticut, this 23rd day of January, A. D. 1932.

CELESTIN BERNE.
